CLOSURE CAP FOR A JAR OR THE LIKE

Lincoln A. Warrell, Mount Holly Springs, Pa., assignor to Pennsylvania Dutch Co., Inc., a corporation of Delaware

Filed Oct. 2, 1967, Ser. No. 8,825

Term of patent 14 years

(Cl. D9—274)

FIG. 1.

FIG. 2.

FIG. 3.

FIG. 1 is a top plan view of a closure cap for a jar or the like showing my new design;

FIG. 2 is a side elevational view; and

FIG. 3 is a bottom plan view.

The essential feature of the design resides in the particular ornamentation applied to the upper surface of the closure cap.

I claim:

The ornamental design for a closure cap for a jar or the like, as shown and described.
